SAFETY RAZOR

Joseph Spencer Kennard, Jr., New York, N. Y.

Application November 4, 1929. Serial No. 404,852

10 Claims. (Cl. 30—12)

This invention relates to safety razors of the kind in which a blade having two cutting edges is utilized. One object of the invention is the provision of such safety razor wherein the component elements are inseparable to obviate the disadvantages of handling a number of separate parts and the risk of loss of such parts. Accordingly, the blade clamping elements, the guard comb and base, while relatively movable to permit the insertion of the blade, are inseparably connected with the handle. More particularly, the guard for the blade is formed with an aperture for the passage of an arm carried with the base, to which arm the handle is secured. My invention can also be applied to sharpening devices.

A further object of the invention is the utilization of movement of the handle with respect to the clamping elements to effect the retention of the blade in cutting position. To this end the handle is formed with a bearing surface adapted to contact with the guard when in operative position of the parts, movement of the handle about its pivotal connection with the arm serving to relieve the clamping effect of the guard and base to permit the insertion and removal of a blade.

The invention also has as an object the adjustment of the tension to which the blade may be subjected in order that the degree of "closeness" of the shave obtained by the razor may be readily controlled. This may be realized by forming the end of the handle which engages the guard comb as a cam surface to press, in varying degree, the guard against the blade and thus depress, more or less, the blade within the concave side of the base. In lieu of a cam surface, the handle may be provided with an adjustable member, such as a screw which may be projected to the desired degree against the guard comb. Another means of realizing this aspect of the invention involves varying the distance between the base and the pivotal connection of the handle with the arm carried by the base. To this end the arm is divided and adjustable securing means for the parts of the arm permit the spacing of the base and handle to the desired degree.

The invention also seeks to permit the razor to be held to the face at different angles in order that no awkward position of the arm is required to bring the blade against the beard at the proper cutting angle. To this end the bearing end of the handle is formed with a plurality of surfaces any one of which when bearing upon the guard will effect the clamping of the blade while the handle is disposed in angular relation therewith.

The invention also has for its object to provide

a safety razor in which the blade is held with its cutting edges very truly parallel to the edges of the guard.

The invention also has for its object to provide for automatic ejection of the blade from the guard to facilitate its ready removal.

The invention also has for its object the provision of a novel and effective blade which may be associated with a razor of the character described to permit the foregoing objects to be realized.

These and other objects of the invention and the means for their attainment will be more apparent from the following detailed description of preferred embodiments thereof, illustrated in the accompanying drawings, in which—

Fig. 1 is a view in side elevation showing the razor according to the present invention, substantially actual size.

Fig. 2 is a view in side elevation on an enlarged and partly in section scale showing the manner in which a blade is clamped between the base and guard through the agency of the handle to which the clamping parts are inseparably connected.

Fig. 3 is a top plan view with the handle omitted for clearness.

Fig. 4 is a horizontal sectional view on the line IV—IV Fig. 2.

Fig. 5 is a horizontal sectional view on the line V—V Fig. 2.

Fig. 6 is a plan view illustrating the comb-edged guard for the blade and showing particularly the elongated aperture for the passage of the arm and the blade positioning lug.

Fig. 7 is a plan view showing the razor blade according to the invention formed with an indent for the reception of the arm on the base and a hole for the positioning lug thereon.

Fig. 8 is a view similar to Fig. 2 showing a second embodiment.

Fig. 9 is an end elevation of the embodiment shown in Fig. 8.

Fig. 10 is a view similar to Fig. 2 but showing a modification of the invention wherein a threaded member in the handle is availed of to vary the clamping effect on the blade.

Fig. 11 is a fragmentary view in side elevation and partly in section showing an adjusting screw adapted to secure the arm to the base, the tightening or loosening of which causes variation in the clamping effect on the blade.

Fig. 12 is a plan view of a modified form of blade.

The blade 1 is adapted to be inserted between clamping elements comprising the convex guard comb 2 and a concave base 3, which are mounted

upon a handle 4 extending generally at right angles thereto. In safety razors hitherto employing a double-edged blade, the handle, guard and base have been separate parts which necessitated assembling and disassembling whenever a blade was to be inserted or extracted. The present invention seeks to obviate the disadvantages of a number of separate parts by mounting the handle 4 as by the pivot 5 upon an arm 6 carried by the base, and forming the guard with an aperture 7 for the passage of the arm. Thus the razor parts are at all times inseparable although the guard 2 may be moved into spaced relation with the base 3 for the insertion or removal of a blade by sliding the guard along the upwardly extending portion 8 of the arm 6. The blade is inserted from the end opposite to the arm and is formed with an indent 9 to fit about the arm and permit the cutting edges 10 to extend the full length of the base. At the opposite end the blade may be formed with a hole 11 for the reception of a rounded lug 12 on the guard 2 which enters a recess 13 in the base 3 and serves as positioning means for that end of the blade and guard. To permit the fingers to grasp the blade easily, the guard 2 is cut away as at 14. The blade may be provided with indents 9^x on each end, as shown in Fig. 12, to fit about the arm 6 and lug 12.

The handle 4 serves to secure the guard and base in clamping relation with the blade by means of the cam surface indicated generally at 15, which bears upon a hardened plug 16 screwed into the threaded aperture 17 in the center of the guard. The cam is so formed that when the handle is substantially at right angles to the clamping elements the desired clamping pressure is exerted, but when the handle is moved angularly about the pivot 5 the cam is turned away from the guard to release the pressure and permit the removal or insertion of the blade. If desired, a cam surface 18 (Fig. 8) may also be formed on the handle at an angle with the first named cam surface which will bear upon the guard with equal effect but which will enable the razor to be used for shaving with the handle at a convenient angle with the plane of the blade. Should the engaging surfaces wear, this may be compensated for, by unscrewing the plug slightly out of the guard, a slot being formed in the plug for the reception of a screw driver or the like for this purpose also by adjustment of the plug 16 the tension of the blade when clamped between the cover guard and concave base may be varied in order that a close shave or one not so close may be secured. To this end also the cam surfaces 15 and 18 (Fig. 8) may be disposed at different distances from the axis of the pivot 5.

A modification of the pressure exerting means is illustrated in Fig. 10 wherein a threaded member 19 is carried by the end of the handle 4 and projects into a recess 20 in the bearing plug 16, the degree of pressure being determined by the extent of projection as will be understood. The degree of pressure may also be varied by varying the distance between the pivot 5 and the base. Thus the horizontal portion 6^x (Fig. 11) of the arm may be separate from the vertical portion 8^x and these portions may be connected by a screw 21 such that by turning the knurled head 22 in one direction or the other, the relation of the two parts is changed.

The guard 2 may be provided with a bent-over projection 20 adapted to be engaged by the toe of handle 4 when it is turned about pivot 5 to release the pressure on the guard 2, and by such

engagement lift the guard 2 away from base 3, as shown in dotted lines Fig. 2, so as to facilitate the removal of the blade 1. Moreover, the arm 6 is preferably provided at its free end with an inwardly turned projection 22, adapted to project through an aperture 24 in the guard 2 when the guard is lifted, and strike against the blade 1 and eject it from the lug 12 in case the blade is lifted with the guard.

The edges 26, 27, of the indent or slot 9 in the blade are preferably formed accurately parallel with the cutting edges 10, and also the edges 26, 27 are made to fit closely against the adjacent sides of arm 6, so as to virtually eliminate looseness or side play of the blade and provide a true parallelism of the cutting edges 10 with the edges of the guard and base.

A stop 25 may be provided on arm 6 to tilt the guard 2 (as shown in dotted lines Fig. 2) when the guard is moved away from the base.

In the embodiments Figs. 8 and 10, the projection 22 on arm 6 may be omitted, as shown.

By the construction described a safety razor having a two edged blade is provided whereof the component elements are normally inseparable, the insertion or extraction of a blade being permitted merely by the angular rotation of the handle, devices being also provided to vary the degree of tension to which the blade is subjected, and to facilitate the removal of the blade.

The invention may receive various other embodiments than those herein specifically illustrated and described.

This application is in part a continuation of my application filed on or about June 17, 1926, Serial No. 116,508.

What is claimed is:

1. In a safety razor, a base, an arm, a single connection between said arm and base near one end, said arm having a portion turned toward and overhanging the middle portion of the base, a guard adapted to fit under said overhanging portion of the arm and over said base, and means on said arm adapted to press said guard and base together to hold a blade, said arm having means at its free end adapted to engage said guard, said means comprising an inwardly turned projection at the free end of said arm and an aperture in said guard, fitting said projection.

2. In a safety razor, a base, an arm, a single connection between said arm and base near one end, said arm having a portion turned toward and overhanging the middle portion of the base, a guard adapted to fit under said overhanging portion of the arm and over said base, and means on said arm adapted to press said guard and base together to hold a blade, and a stop on said arm for contacting with said guard as the guard is moved away from said base whereby said parts coact to tilt said guard.

3. In a safety razor, a base, an arm, a single connection between said arm and base near one end, said arm having a portion turned toward and overhanging the middle portion of the base, a guard fitting under said overhanging portion of the arm and over said base, and means on said arm for pressing said guard and base together to hold a blade, said guard having an aperture therein fitting said arm and inseparably connecting said guard and base, said arm and base being so constructed and arranged that a blade held upon said base is free to be used at two opposite sides for cutting, and removed endwise when released.

4. In a safety razor, a base, an arm having a

- single connection to said base in the longitudinal axis and near one end only of said base, said arm having a portion turned toward and overhanging the middle portion of the base, a guard fitting under said overhanging portion of the arm and over said base, and means on said arm for pressing said guard and base together to hold an interposed blade, said arm and base being so constructed and arranged that a blade held upon said 5 base is free to be used at either of its two opposite sides for cutting, and is removable axially of the base when released. 80
5. In a safety razor, a base, an arm having a single connection to said base in the longitudinal axis and near one end only of said base, said arm having a portion turned toward and overhanging the middle portion of the base, a guard fitting under said overhanging portion of the arm and over said base, and a handle pivoted 10 on said arm and having a part which, upon turning of said handle to its position of use, presses said guard and base together to hold an interposed blade, said arm and base being so constructed and arranged that a blade held upon said 15 base is free to be used at either of its two opposite sides for cutting, and is removable axially of the base when released. 85
6. In a safety razor, a blade, an arm having a single connection to said base in the longitudinal axis and near one end only of said base, said arm having a portion turned toward and overhanging the middle portion of the base, a guard fitting under said overhanging portion of the arm and over said base, means on said arm for pressing 20 said guard and base together to hold an interposed blade, and means on said arm for separating a blade from the guard when the guard is lifted, said arm and base being so constructed and arranged that a blade held upon said base 25 is free to be used at either of its two opposite sides for cutting, and is removable axially of the base when released. 90
7. In a safety razor, a base, an arm having a single connection to said base in the longitudinal axis and near one end only of said base, said arm having a portion turned toward and overhanging the middle portion of the base, a guard fitting under said overhanging portion of the arm and over said base, and means on said arm for pressing 30 said guard and base together to hold an interposed blade, and means on said arm for separating a blade from the guard when the guard is lifted, said arm and base being so constructed and arranged that a blade held upon said base 35 is free to be used at either of its two opposite sides for cutting, and is removable axially of the base when released. 95
8. In a safety razor, a base, an arm having a single connection to said base in the longitudinal axis and near one end only of said base, said arm having a portion turned toward and overhanging the middle portion of the base, a guard fitting under said overhanging portion of the arm and over said base, and a connection between 40 said guard and said pressing means for lifting said guard away from said base, said arm and base being so constructed and arranged that a blade held upon said base is free to be used at either of its two opposite sides for cutting, and is removable axially of the base when released. 100
9. In a safety razor, a curved base, an arm having a single connection to said base in the longitudinal axis and near one end only of the base, said arm having a portion turned toward and overhanging the concave middle portion of the base, a guard between said overhanging portion of the arm and over said base, a handle, means on said arm for pressing said guard and base together to hold an interposed blade, and a razor blade having a longitudinal slot near one 45 end to fit said arm, said arm, blade and base being so constructed and arranged that a blade held upon said base is free to be used at either of its two opposite sides for cutting, and is removable of the base when released. 105
10. In a safety razor, a base, an arm, having a single connection to said base in the longitudinal axis and near one end only of said base, said arm having a portion turned toward and overhanging the middle portion of the base, a guard fitting under said overhanging portion of the arm and over said base, and a handle pivoted to said 50 arm for pressing said guard and base together to hold an interposed blade, said arm and base being so constructed and arranged that a blade held upon said base is free to be used at either of its two opposite sides for cutting and is removable axially of the base when released, said guard having an adjustable bearing plug thereon, and said handle having a cam arranged 55 to bear on said plug. 110
